Iron holder, especially for electric irons, and improvements thereto, comprising a base plate having a lower edge formed with an upwardly inclined flange, and a side edge formed with a stationary inwardly curved flange, a horizontally adjustable flange being positioned at the other side edge of the base plate, and a cord holder being integrally formed with the flange.

UNITED STATES PATENT OFFICE

2,517,953

IRON HOLDER

Raymond Wiinikka, Grand Rapids, Mich.

Application October 18, 1948, Serial No. 551553

2 Claims. (Cl. 248—117.7)

1

The present invention relates to new and useful improvements in holders for electric or other irons and more particularly to a wall attached holder in which the iron may be supported, when not in use.

An important object of the invention is to provide a wall attached iron holder which is supported away from the wall or other supporting structure to provide an air space behind the holder and iron to facilitate cooling of the iron.

Another object of the invention is to provide an adjustable iron retaining flange at one edge of the holder to accommodate irons of various sizes.

A still further object is to provide a cord support at one side of the holder on which the electric cord of the iron may be wound.

A still further object is to provide a device of this character of simple and practical construction, which is efficient and reliable in use, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view showing the iron holder with the iron removed therefrom;

Figure 2 is a side elevational view showing the iron supported in position in the holder;

Figure 3 is a rear elevational view;

Figure 4 is a transverse sectional view taken substantially on a line 4—4 of Figure 1;

Figure 5 is an enlarged fragmentary sectional view showing the guides for the adjustable flange and taken on a line 5—5 of Figure 1, and;

Figure 6 is a perspective view of the adjustable flange and cord support.

Referring now to the drawings in detail wherein for the purpose of illustration I have disclosed a preferred embodiment of the invention the numeral 5 designates the iron holder generally and which is constructed of a light weight metal plate 6 shaped in the form of the base of an electric or other iron, the ends of the plate being formed with legs 7 formed with attaching flanges 8 by means of which the plate is secured to a wall or other supporting structure 9. The legs 7 hold the plate 6 away from the wall to provide an air space between the holder and the surface of the wall.

2

The lower edge of the plate 6 is formed with an upwardly inclined flange 10 and one side edge of the plate 6 is formed with a stationary inwardly curved flange 11.

- 5 A horizontally adjustable flange 12 is positioned at the other side edge of the plate 6 and is formed at the outer end of a plate 13 which is positioned behind the plate 6 and slidable in upper and lower guide lugs 14 struck in a rearwardly direction from the surface of the plate 6. The adjustable plate 13 is formed with a horizontally extending slot 15 and a bolt 16 is countersunk in the front surface of plate 6 and positioned in slot 15 with a wing nut 17 on the bolt behind the plates 6 and 13 to hold the adjustable plate 13 in its horizontally adjusted position. The flange 12 may thus be adjusted laterally at one side of the plate 6 to accommodate irons of various sizes.
- 10 A cord holder 19 is integrally formed with the flange 12 by means of a web 20 which extends outwardly from the flange to support the cord holder outwardly at the side of the plate 6. The cord holder 19 is forked at each end as shown at 15 20 to retain an ironing cord thereon when wound on the cord holder.

25 The outer surface of plate 6 and the inner surfaces of flanges 11 and 12 are provided with a suitable lining 21 to form heat insulation means between an iron 22 and the iron holder when the iron is placed therein.

30 In the operation of the device the plate 6 is secured to a wall or other suitable supporting structure as indicated in Figure 2 of the drawings and the iron 22 placed between flanges 11 and 12 and with the lower edge of the iron resting on the lower flange 10.

35 The iron is thus securely held in the holder when not in use and may be removed by raising the iron upwardly until released from the side flanges 11 and 12.

40 In view of the foregoing description taken in conjunction with the accompanying drawings it is believed that a clear understanding of the construction, operation and advantages of the device will be quite apparent to those skilled in this art. A more detailed description is accordingly deemed unnecessary.

45 It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An iron holder comprising a wall attached plate, flanges carried by the plate holding an iron in an upright position thereon a web formed as a unitary structure with and projecting outwardly from one of said flanges, and a cord holding reel of sheet metal construction integrally formed at the outer edge of the web and having a fork at each of its opposite edges.

2. An iron holder comprising a wall attached plate, a fixed flange at one edge of the plate, and a unitary flange and cord holder at an opposite edge of the plate and comprising a second plate attached to the first plate for inward and outward adjustment with respect thereto, a forwardly projecting flange forming plate projecting forwardly from the outer edge of the second plate in op-

posed relation to the fixed flange, a web projecting outwardly from the forward edge of the flange forming plate, and a cord holding plate at the other edge of the web and having a fork at each of its opposite end edges.
